UNITED STATES PATENT OFFICE.

EUGENE C. JEWETT, OF EAGLEGROVE, IOWA.

SPADE.

No. 809,807.

Specification of Letters Patent.

Patented Jan. 9, 1906.

Application filed July 3, 1905. Serial No. 268,064.

To all whom it may concern:

Be it known that I, EUGENE C. JEWETT, a citizen of the United States, residing at Eagle-grove, in the county of Wright and State of Iowa, have invented certain new and useful Improvements in Spades; and I do hereby declare the following to be a full, clear, and exact description of the invention, such as will enable others skilled in the art to which it appertains to make and use the same.

My invention relates to spades, and more particularly to that class of devices of this character technically known as "skeleton" spades.

The object of the invention is to provide a spade which is constructed of forged metal and of two parts—to wit, a head and a bit—each of which is formed in a single piece and the two adapted to be welded together at points where but little strain is received during the use of the tool.

Another object is to form the body of the spade of tines which are of a peculiar construction, whereby the spade can be readily inserted into the ground and will stand any strain to which it is subjected in ordinary usage.

A still further object is to provide tines which are shaped in a peculiar manner so that their size can be reduced without proportionately reducing their strength.

With the above and other objects in view the invention consists of a head having tine-sections extending from it, said head and sections being formed of a single forging and adapted to be welded to a bit having tine-sections extending from it. When the two parts are assembled, the tines are continuous from the head to the bit and taper toward the bit, they being of greater thickness at the head than at the bit. The central tine is tapered in cross-section from front to rear, so that a great saving of metal results without in any way reducing the strength or efficiency of the tine.

The invention also consists in further novel construction and combination of parts, hereinafter more fully described and claimed.

In the accompanying drawings I have shown the preferred form of my invention.

In said drawings, Figure 1 is a front elevation of a spade constructed in accordance with my invention. Fig. 2 is a longitudinal section therethrough with the handle removed, and Fig. 3 is a section on line 3-3 of Fig. 2. 55

Referring to the figures by numerals of reference, 1 is a head having preferably three tine-sections, two extending therefrom—one at each end and one at the center. These sections and head are formed of a single forging, 60 and a shank 3 extends from the center of the head and is adapted to be secured within one end of a handle 4 in any suitable manner. The bit of the spade consists of a sharpened blade 5, from which extend tine-sections 6. 65 These sections are located at the end and center of the blade and are adapted to be welded to the sections 2 at points between the centers of the completed tines and the head 1. The spade receives less strain at this point than 70 any other, and therefore by welding the parts at these points the strength of the spade is not impaired by constructing it in the manner herein described.

By referring to Fig. 2 it will be noticed 75 that the tines are thicker at the head than at the blade. By tapering them in this manner the blade can be forced into the ground more readily than where they are of the same thickness throughout their lengths. 80

Fig. 3 shows that the central tine has beveled sides which taper from front to rear. A tine constructed in this manner permits the saving of considerable metal without reducing the strength of the tine. 85

In the foregoing description I have shown the preferred form of my invention; but I do not limit myself thereto, as I am aware that modifications may be made therein without departing from the spirit or sacrificing the 90 advantages thereof, and I therefore reserve the right to make such changes as fairly fall within the scope of my invention.

Having thus fully described my invention, what I claim as new, and desire to secure by 95 Letters Patent, is—

A skeleton spade formed of two parts and consisting of a head having integral tine-sections and a sharpened blade having integral tine-sections, the tine-sections of the head and 100

blade being permanently connected at points between the center and head of the spade and the tines formed by the sections being of constantly-decreasing thickness from the head to the blade, one of said tines having beveled side faces.

In testimony whereof I have signed my name

to this specification in the presence of two subscribing witnesses.

EUGENE C. JEWETT.
